UNITED STATES PATENT OFFICE.

JOSEPH GOULBOURN, OF LEICESTER, ENGLAND, ASSIGNOR TO UNITED SHOE MANUFACTURING COMPANY, OF PATERSON, NEW JERSEY, A CORPORATION OF NEW JERSEY.

SOLE-LEVELING MACHINE.

1,114,253.

Specification of Letters Patent. Patented Oct. 20, 1914.

Application filed May 4, 1914. Serial No. 836,185.

To all whom it may concern:

Be it known that I, JOSEPH GOULBOURN, a subject of the King of Great Britain, residing at Leicester, in the county of Leicestershire, England, have invented certain new and useful Improvements in Sole-Leveling Machines; and I do hereby declare the following to be a full, clear, and exact description of the invention, such as will enable others skilled in the art to which it appertains to make and use the same.

The invention relates to sole leveling machines, and more particularly to that class of machines in which the leveling operation is effected by the rubbing action of a rotating leveling roll which is applied under pressure to the sole of a shoe, and is caused to travel along the shoe sole by relative movement of the roll carrier and jack upon which the shoe is supported. In operating upon certain classes of work with machines of this type it is desirable that the roll be moistened, and the object of the present invention is to provide means for automatically controlling the supply of moistening liquid to the leveling roll or rolls, so that the shutting off of the supply of liquid when the machine is out of operation, and the proper moistening of the rolls during the operation of the machine, will be insured.

To these ends the invention contemplates the provision in a leveling machine of the above type of means controlled by the machine for stopping the supply of liquid to the roll when the machine is at rest. Any suitable means may be employed for thus shutting off the supply of liquid to the roll, and this means may be operated by any suitable moving part of the machine. It is preferred, however, to so construct the means for controlling the supply of liquid to the roll that it will operate to start and stop the supply of liquid at predetermined times in each leveling operation, so that the predetermined quantity of liquid requisite for securing the most efficient operation upon the shoe may be automatically delivered to the roll during each leveling operation.

The various features of the invention will be readily understood from an inspection of the drawings, and the following detailed description of the mechanism illustrated therein.

In the drawings, Figure 1 is a sectional

elevation showing so much of a sole leveling machine as is necessary to illustrate the application of the preferred form of the present invention thereto; Fig. 2 is a sectional plan view on an enlarged scale taken on the line 2—2 of Fig. 1; Fig. 3 is a vertical section of the valve which controls the supply of liquid to the distributing device; Fig. 4 is a section on line 4—4 of Fig. 3; and Fig. 5 is a vertical section of the liquid distributing device.

The machine shown herein comprises two sole supporting jacks 2, and two coöperating sole pressing rolls 4, one only of each of these parts being shown in the drawings. Each of the rolls 4 is journaled at the end of a carrier arm 6, springs 8 acting upon the arm to maintain the roll in contact with the sole of a shoe supported on the jack. The rolls are rotated in their carriers by mechanism which need not be described, since it forms no part of the present invention. 75

The machine is provided with a cam 10, and with mechanism by which each jack in turn can be coupled to this cam so that the jack is oscillated beneath the leveling roll to cause the point of operation of the roll to travel along the shoe sole. This mechanism may be the same as that shown and described in Patent No. 555,548, March 3, 1896, and need not be herein specifically described.

According to the present invention, the frame of the machine is provided with a bracket 12 which supports a water tank 14 secured thereto by a screw 16, which tank has an outlet pipe provided with a tap 18 by means of which the flow of liquid from the tank may be turned on or off or regulated as required. Screwed upon, or otherwise secured to the end of the pipe from the tank is a member 20 in which is formed a conical recess which constitutes a seating for a conical valve spindle 22 (see particularly Figs. 3 and 4). The member 20 is provided with three holes, one 24 leading from the said recess to the outlet pipe of the tank, and two others 26 leading from the recess to nozzles 100 28 formed on the member 20. The nozzles are connected by flexible tubes 30 to two liquid distributing devices 32, one for each leveling roll. The valve spindle 22 is bored longitudinally at 34, and is also provided with radial holes 36 which extend into the longitudinal bore 34, and which, when the spindle is turned into the open position as

shown by the dotted lines in Fig. 4, are brought into register with the holes 24 and 26 in the member 20. The spindle 22 is retained in the recess of the member 20 by means of a pair of nuts 38 which are screwed upon an extension 40 which projects from the spindle through a washer 42 that rests on the top of the member 20.

The lower end of the spindle 22 is cup-shaped, and receives the ball-shaped end of a vertical rod 44 which is carried in ears 46 and 48 formed on the bracket 12, and is held from longitudinal movement by a pair of collars 50 and 52 attached to the rod on each side of the ear 48. The ends of a pin 54, passing through the ball-shaped end of the rod 44, engage the walls of vertical slots, one of which is shown at 56 (Fig. 3), cut in the cup-shaped portion of the spindle 22. This method of connection insures that the spindle 22 and rod 44 shall turn as one without danger of breakage or jamming of the parts, should the axes of the rod and spindle be slightly out of alinement. From the collar 50 projects an arm 54 carrying a roll 56 which is held by means of a spring 58 attached at one end to a hook 60 (see Fig. 2) on the collar 52, and at the other end to a hook 62 on the bracket 12 in position to be engaged by a wedge-shaped cam or dog 64 carried by the cam 10 which is employed to oscillate the jacks. The spring 58 tends to maintain the valve closed. The collar 52 is provided with a stop 66 which engages with a coöperating stop face formed upon the bracket 12 when the valve is closed by the action of the spring 60.

Each of the liquid distributing devices 32 comprises a member 68 from which extends a damping pad 70 of felt or light material that bears upon the corresponding leveling roll 4. The pad 70 passes through a slot in the member 68, its inner end being located in a chamber 72 formed in the member. The member 72 is mounted upon a casing 74 which contains a portion of the mechanism for rotating the roll, or may be otherwise so arranged that it partakes of the movements of the roll carrier. Screwed into the member 68 is a part 76 which comprises a nozzle 78 which receives one of the flexible tubes 30 connected with the two nozzles of the valve member 20. Passing through the nozzle 78 is a hole 80 which leads into a recess 82 in the part 76, and from thence by way of an aperture 84 and a hole 86 into the chamber 72, so that the end of the pad within the chamber receives the liquid delivered from the supply tank by the opening of the valve 22. The top of the aperture 84 is conical in shape, and is adapted to receive the conical end of an adjusting screw 88 to regulate the rate of flow of liquid to the pad. The screw is screwed into

the nozzle 78 and is provided with a lock nut 90 so that it may be locked in adjusted position.

In the operation of the machine a shoe is placed upon one of the jacks 2, the jack is then coupled to its guiding mechanism, and the machine started. The cam 10 then operates to oscillate the jack beneath the leveling roll 4, and during this rotation of the cam the dog 64 strikes against the roll 56, thereby operating the rod 44 and opening the valve to allow liquid to flow from the tank 14 to the delivering devices 32. When the dog 64 passes from engagement with the roll 56, the spring 58 acts to turn the rod 44 reversely, and closes the valve so that the supply of liquid from the tank is suspended. After the leveling operation upon the shoe has been completed, the machine is automatically brought to rest, and the other jack, upon which the operator has placed another shoe while the machine was operating upon the preceding shoe, is now coupled to its actuating mechanism and the machine again started.

It will be noted that by this construction, while the machine is at rest the supply of liquid from the tank is stopped, and further, that the amount of liquid which is delivered to the distributing devices is predetermined by the machine as the valve is opened by the action of the dog 64 and spring 58 for a predetermined time in each sole leveling operation. The quantity of liquid, however, is under the control also of the operator, since by opening the tap 18 more or less, he can regulate the amount of liquid delivered to both the delivering devices 32, or by means of the adjusting screw 88 he can control the amount of liquid delivered from each of said devices.

Although for the sake of simplicity only one automatically controlled valve is used to supply liquid to both of the leveling rolls, and this valve is controlled from the cam that is common to both jacks, it will be understood that separate valves may be employed for each jack, and that the valve or valves may be controlled by the movements of other parts of the machine. Moreover, although it is preferred to automatically control the opening and closing of the valve through which liquid is supplied to the distributing devices, it will be understood that this is not essential to the broader features of the invention, and the automatic stopping of the supply of liquid to the rolls when the machine is not in operation may be otherwise effected without departing therefrom. It will also be understood that the specific construction and arrangement of the parts may be otherwise varied and modified as found desirable or best suited to the con-

struction of machine in which the invention is embodied.

Having explained the nature and object of the invention, and specifically described 5 one form of machine in which it may be embodied, what is claimed is:—

1. A sole leveling machine, having in combination, a leveling roll and shoe supporting jack relatively movable to transfer the roll 10 along the sole of a shoe supported on the jack, a roll moistening device, and automatically controlled means for stopping the supply of liquid to the moistening device when the machine is at rest.
- 15 2. A sole leveling machine, having, in combination, a leveling roll and shoe supporting jack relatively movable to transfer the roll along the sole of a shoe supported on the jack, a roll moistening device, automatically controlled means for stopping the 20 supply of liquid to the moistening device when the machine is at rest, and means for regulating the rate at which the liquid is delivered to the moistening device.
- 25 3. A sole leveling machine, having, in combination, a leveling roll and shoe supporting jack relatively movable to transfer the roll along the sole of a shoe supported on the jack, a roll moistening device, and 30 means operating automatically to start and stop the supply of liquid to the moistening device during each leveling operation.
- 35 4. A sole leveling machine, having, in combination, a leveling roll and shoe supporting jack relatively movable to transfer the roll along the sole of a shoe supported on the jack, a roll moistening device, means operating automatically to start and stop 40 the supply of liquid to the moistening device during each leveling operation, and means for regulating the rate at which the liquid is delivered to the moistening device.
- 45 5. A sole leveling machine, having, in combination, a leveling roll and shoe sup-

porting jack relatively movable to transfer 45 the roll along the sole of a shoe supported on the jack, a roll moistening device, a valve for controlling the supply of liquid to the roll, and means operating automatically to open and close the valve at predetermined 50 times during each leveling operation.

6. A sole leveling machine, having, in combination, a leveling roll and shoe supporting jack relatively movable to transfer 55 the roll along the sole of a shoe supported on the jack, a roll moistening device, a valve for controlling the supply of liquid to the roll, means operating automatically to open and close the valve at predetermined 60 times during each leveling operation, and a regulating valve for determining the rate at which the liquid is delivered to the moistening device.

7. A sole leveling machine, having, in 65 combination, a leveling roll and shoe supporting jack relatively movable to transfer the roll along the sole of a shoe supported on the jack, a roll moistening device, a valve normally closed for controlling the 70 supply of liquid to the roll, and a cam operating to periodically open the valve during each leveling operation.

8. A sole leveling machine, having, in 75 combination, leveling rolls and shoe supporting jacks relatively movable to transfer the rolls along the soles of shoes supported on the jacks, a roll moistening pad and distributing device for each roll, a valve for controlling the supply of liquid to the distributing devices, and means for automatically opening and closing the valve at predetermined 80 times during each leveling operation.
